UNITED STATES PATENT OFFICE.

ERIC T. SAMUELSON, OF CHICAGO, ILLINOIS, ASSIGNOR TO R. WILLIAMSON & COMPANY, OF CHICAGO, ILLINOIS, A CORPORATION OF ILLINOIS.

LIGHTING FIXTURE.

Application filed March 17, 1926. Serial No. 95,176.

This invention relates to lighting fixtures and more particularly to those having bracket arms which project from the body of the fixture.

The object of the invention is to provide a strong and substantial fixture and to engage the arms with the body in a novel manner which will hold them rigid with respect to the body and prevent them from working loose.

In the accompanying drawings illustrating the invention

Fig. 1 is an elevation, partly in section, showing a lighting fixture embodying the invention;

Fig. 2 is a top plan view, partly broken away, of the fixture shown in Fig. 1;

Fig. 3 is an enlarged detail sectional view showing the means whereby the arm is rigidly secured in the body of the fixture; and

Fig. 4 is a sectional view on the line 4—4 of Fig. 3.

Referring to the drawings, the body of the fixture comprises two parts, the bottom part 5 and the top part 6 which are rigidly secured together by the tie rod 7. In this adaptation of the invention four arms 8 are carried by the body, but a description of one arm and the manner in which it is secured to the body will be sufficient since all the other arms are secured in the same way.

Referring to Figs. 3 and 4, the arm 8 projects through an opening 9 in the bottom part 5 of the body and extends into a socket 10 in the top part 6 of the body. This socket is pressed into the sheet metal forming the top of the body and is of a size and shape adapted to receive snugly the upper end of the arm. That part of the arm within the body is an exteriorly screw-thread 11 to receive a nut 12. A collar 13 rigidly secured on the arm is arranged to engage the outer face of the body and the nut 12 is screwed down on the arm to clamp the bottom part of the body between itself and the collar. The parts are constructed and proportioned so that when the collar engages the bottom part of the body the upper end of the arm will be seated snugly in the socket 10 and when the nut is screwed down on the arm against the bottom part of the body the parts will be held rigidly in this position. To prevent the arm from being twisted when secured to the body I provide the collar with a flange 14 of irregular shape

to fit within a depression of similar shape in the bottom part of the body. In the drawings the flange and the depression are generally circular with flattened sides 16 and these sides are of sufficient length so that when the collar is seated in the depression it will be impossible to twist the arm without breaking or otherwise damaging the parts.

The conductor wires 17 project through a slot 18 formed in the wall of the upper end of the arm so that the parts can be easily assembled. It will be readily understood that the arms can be engaged with the bottom part of the body and the flange of the collar seated in the depression 15 and the nut 12 tightened against the bottom part of the body and the wires arranged in the slot 18 after which the two parts of the body are assembled and secured together by any suitable means.

My invention provides a simple means for rigidly anchoring the arm to the body of a lighting fixture so that it will be held in fixed position against lateral or rotative movement. The invention comprises few parts which are easily assembled without special skill, and they can be easily separated if occasion requires.

I am aware that changes in the form, construction and arrangement of parts may be made without departing from the spirit or sacrificing the advantages of the invention and I reserve the right to make all such changes as fairly fall within the scope of the following claims.

I claim:

1. A lighting fixture comprising a body having a socket and an opening therein, an arm arranged outside of said body and having its upper end projecting upwardly through said opening and seated in said socket, means arranged on the arm to engage the lower end of said body and means arranged on said arm and within said body for rigidly securing said arm thereto.

2. A lighting fixture comprising a body having a socket therein and an opening in alignment with the socket, and an arm having a threaded portion projecting through the opening and having its upper end seated in said socket and provided in that portion within the body with a slot to receive the conductor wires, means arranged on said arm for engaging the lower edge of said

body, and threaded means mounted within said body and engaging said arm for clamping said arm on said body.

3. A lighting fixture comprising a body having a socket and an opening therein, an arm projecting through the opening and having its end seated in the socket, a collar on the arm to engage an outside face of the body, that portion of the arm within the body being screwthreaded, and a nut engaged with the arm within the body and clamping a part of the body between itself and said collar.

4. A lighting fixture comprising a body having a top and a bottom, means for securing the parts of the body together, the bottom of the body having a depression therein of irregular shape and an opening in said depression, the top of the body having a socket therein, an arm projecting through said opening and having its end seated in said socket, that portion of the arm within the body being screwthreaded, a collar rigid on said arm and having a flange irregularly shaped to seat in the depression in the bottom of the body, and a nut on the arm within the body and clamping a part of the bottom of the body between itself and the flange of the collar.

5. A lighting fixture comprising a top having a socket formed therein, a bottom having an opening therein in alignment with said socket, said bottom having a recess formed therein surrounding said opening, means for connecting said top and bottom together, an arm projecting through said opening and engaging said socket, means arranged on said arm and disposed in said recess for en-

gaging the outside of said bottom, and means mounted on said arm for engaging the inside of said bottom for rigidly clamping said arm to said bottom.

6. A lighting fixture comprising a top having a socket formed therein, a bottom having an opening therein in alignment with said socket, said bottom having a depression with flattened sides formed therein surrounding said opening, means for connecting the top and bottom together, an arm having a threaded portion projecting through said opening and engaging said socket, means arranged on said arm and disposed in said depression for engaging the outside of said bottom and threaded means mounted on the threaded portion of said arm for engaging the inside of said bottom for rigidly clamping said arm to said bottom.

7. A lighting fixture comprising a top having a socket formed therein, a bottom having an opening therein in alignment with said socket, said bottom having a depression with flattened sides formed therein surrounding said opening, means for connecting the top and bottom together, an arm projecting through said opening and having the upper end thereof engaging said socket, a circular collar having flattened sides mounted on said arms and disposed in said recess for engaging the outside of said bottom and a nut mounted on the threaded portion of said arm for engaging the inside of said bottom for rigidly clamping said arm to said bottom, said arm having an opening provided in the side thereof to receive the conductor wires.

ERIC T. SAMUELSON.
